By his Attorney, *Howard S. Kneedler*

UNITED STATES PATENT OFFICE.

HOWARD S. KNEEDLER, OF PHILADELPHIA, PENNSYLVANIA.

DESIGN FOR TICKING OR SIMILAR FABRIC.

SPECIFICATION forming part of Design No. 17,428, dated July 5, 1887.

Application filed June 3, 1887. Serial No. 240,189. Term of patent 7 years.

To all whom it may concern:

Be it known that I, HOWARD S. KNEEDLER, a citizen of the United States, and a resident of Philadelphia, Pennsylvania, have invented 5 a new and original Design for Ticking and other Woven Fabrics, of which the following is a specification.

My design for ticking and similar woven fabrics is illustrated in the accompanying 10 drawings, in which--

Figure 1 is a view showing the general effect; and Fig. 2 is a view showing the detailed characters of the striped bars.

My design consists of alternating wide and 15 narrow bars A and B on a ground color, G, Fig. 1. The narrow bar B consists of a single dark-colored stripe, b, with a shading-stripe, S, on one side. The wide stripe A consists of a number of narrow light and dark stripes, a 20 and a', alternated with one another, there being in the present instance six dark-colored stripes, a', with five intermediate and alternating white stripes, a. At one side of the whole bar A is a shading-stripe, S, corresponding

with the shading-stripe on the bar B—that is, 25 the shading-stripes in all the bars are on the same side, at the right-hand side in the illustration.

I claim—

The design for ticking and similar woven 30 fabrics, said design consisting of alternating wide and narrow bars A and B on a ground, G, the wide bar A consisting of a number of narrow light and dark stripes, a and a', alternating with each other, and a shading-stripe, S, 35 on one side of the bar, while the narrow bar B consists of a single stripe, b, with a shading-stripe S on the same side as the shading-stripe of the wide bar, all substantially as shown and set forth.

In testimony whereof I have signed my name to this specification in the presence of two subscribing witnesses.

HOWARD S. KNEEDLER.
